[57] CLAIM

The ornamental design for an articulated rear view mirror for attachment to eye glasses, as shown and described.

DESCRIPTION

FIG. 1 is a perspective view of an articulated rear view mirror for attachment to eye glasses showing our new design, it being understood that the broken lines are for illustrative purposes only;

FIG. 2 is a side elevation view thereof;

FIG. 3 is a side elevation view thereof opposite to that shown in FIG. 2;

FIG. 4 is a top plan view thereof;

FIG. 5 is a bottom plan view thereof;

FIG. 6 is an end elevation view thereof; and

FIG. 7 is an end elevation view thereof opposite to that shown in FIG. 6.
